SALAD BOWL COMBINATION

Kurt M. Vorchheimer, 92 Pinehurst Ave.,
New York, N.Y. 10033

Filed Nov. 17, 1972, Ser. No. 307,590

Term of patent 14 years

Int. Cl. D7—01

U.S. Cl. D7—4

Fig.1

Fig.3

FIG. 1 is a top plan view of a salad bowl combination showing my new design;

FIG. 2 is a side elevational view thereof; and

FIG. 3 is a bottom plan view thereof.

I claim:

The ornamental design for a salad bowl combination, substantially as shown.
